UNITED STATES PATENT OFFICE.

GEORGE S. GATCHELL, OF ELIZABETH, NEW JERSEY, ASSIGNOR TO THE SINGER MANUFACTURING COMPANY, A CORPORATION OF NEW JERSEY.

WORK-CLAMP FOR SEWING-MACHINES.

SPECIFICATION forming part of Letters Patent No. 789,126, dated May 2, 1905.

Application filed April 26, 1904. Serial No. 204,945.

To all whom it may concern:

Be it known that I, GEORGE S. GATCHELL, a citizen of the United States, residing at Elizabeth, in the county of Union and State 5 of New Jersey, have invented certain new and useful Improvements in Work-Clamps for Sewing-Machines, of which the following is a specification, reference being had therein to the accompanying drawings.

10 This invention has for its object to provide a simple and effective form of work-clamp capable when closed upon the material of stretching the latter for the stitching operation; and it consists, essentially, in the 15 combination, with the usual spring-pressed clamping-lever, of a foot comprising two clamping-jaws, each provided at opposite ends with lateral ears, and common pivotal connections intermediate said clamp-lever 20 and the lateral ears of said jaws. The pivotal connections of the clamping-jaws with the lever by which they are carried are preferably laterally adjustable in order to permit the jaws to be lined up with the stitch-forming mechanism and the positions and 25 direction of motion of the work feeding and shifting slides by which the clamp is carried.

In work-clamps for buttonhole-machines heretofore unprovided with special means for 30 spreading the jaws when closed upon the goods; so as to stretch the latter for the stitching operation, in certain instances the jaws have been attached to their carriers in such manner as to yield laterally when forced 35 upon the material owing to their outward inclination in respect of the direction of opening and closing movement of the clamp. As it has been necessary to engage the material comparatively close to the stitching-line, the 40 divergence of the jaws has necessarily been so slight as to require a considerable pressure, and therefore to involve the use of a strong clamp-spring to effect the requisite stretching of the material. This was objectionable for two reasons. First, because the 45 excessive pressure upon the clamp-jaws produced deep indentations in the material, and therefore marred its appearance, and, second,

because the employment of a heavy clamp-spring required a corresponding effort on the 50 part of the operator to open the clamp for removal or shifting of the material, involving excessive exertion in such operation.

By the present improvement in the employment of the toggle principle, whereby a 55 comparatively light clamping pressure is sufficient to give the requisite stretching movement to the clamping-jaws, I am enabled by simple means and with little effort on the part of the operator to secure as effective operation of the clamp in holding and stretching the material as has been heretofore attained by means of separate and independent holding and clamping devices for the work in buttonhole-machines of different types. 60

By providing the clamping-jaws with offset common pivotal connections not only are the jaws adapted to insure compensation in the pressure upon the work when the thickness of the material is variable, but the 70 initial engagement of the operative edges of the jaws with the work when the clamp is closed upon the latter affords a resistance whereby such work-engaging edges are constituted movable fulcra about which the 75 common offset pivot moves toward the work, thereby forcing such edges apart and with them the adjacent material of which the intermediate portion is thus drawn taut across the throat-plate. 80

The invention will be understood by reference to the drawings annexed, in which—

Figure 1 is a plan of a clamping-foot embodying the present invention with the adjacent portion of the clamp-lever. Fig. 2 is a 85 side elevation of the same with the co-operating clamp-slide represented in section. Figs. 3 and 4 are end elevations of the clamp, showing the latter in open and closed positions, with the material interposed between the 90 jaws and the clamp-plate constituting the lower member of the clamp. Figs. 5 and 6 are perspective views, respectively, of one of the clamping-jaws and one of the pivoting-brackets by which the same is secured to the 95 clamp-lever. Fig. 7 is an end elevation

similar to Fig. 4, but showing the relative positions of the opposed clamping-jaws when engaging material of uneven thickness.

I have shown the present improvement embodied in a work-clamp designed for application in the buttonhole cutting and stitching machine disclosed in the application of E. B. Allen, filed April 21, 1904, Serial No. 204,160, the general construction and mode of operation of the clamp being substantially the same as the primary clamp therein shown and described, excepting in the construction of the foot of the latter.

The clamp-lever 1 is shown provided with a forked forward end, to the extremities of which is connected, by means of the fastening-screws 2, a flat carrying plate or carrier 3, having a central rectangular opening 4 for the passage of the cutting-knife and needle and provided at the ends with the transverse slots 5, to which are loosely fitted the rectangular bosses 6, formed upon the base of the bracket 7 and adjustably secured to the plate 3 by means of fastening-screws 8. Each of the clamping-jaws consists of a flat bar 9, with perforated lateral ears 10, the lower edge of one of each and that of the bar 9 being serrated to insure the firm hold of the jaw upon the material when forced upon the same by the clamp-lever 1. The lateral ears 10 are provided with pivot-holes 11, and when the ears of the opposed clamping-jaws at corresponding ends are inserted between the perforated lugs of the bracket 7 they are pivoted together and to such bracket by means of the common pivot-screws 12. Each of the jaws 9 is pressed normally downward by means of the flat spring 13, secured to the under side of the plate 3 by the screws 14, the end of one of the ears 10 upon each clamp-jaw 9 offering a shoulder 15 for engagement with the other clamp-jaw to limit the closing movement of the jaws under the action of their respective springs 13.

In the use of the clamp as above described the clamp-lever 1 is raised from the slide-plate 16 in opposition to its spring by the usual means and the material 17 introduced, the jaws 9 thus assuming the position represented in Fig. 3, with the shoulder 15 of the lug 10 carried by each jaw 9 in engagement with the inner face of the other jaw under the action of the spring 13. Upon the depression of the clamp-lever 1, and consequent engagement of the serrated edges of the jaws 9 with the material, the ears 10, in conjunction with the pivotal pins 12, produce a wedging action between the jaws, which tends to force them apart to stretch the material intermediate their work-engaging edges, one or both of the upper edges of the jaws becoming seated against the plate 3 or interposed springs 13. As the operative or work-engaging edges of the jaws 9 are disposed upon opposite sides of the line of stitching (indi-

cated in the drawings by the longitudinal slot in the throat-plate) and as such edges are parallel and equal in length, their action upon the material is to stretch the intermediate portion thereof uniformly throughout the length of buttonhole, which is evidently essential to the production of a perfect buttonhole.

As indicated in Fig. 7, the present clamping-foot possesses material advantages over others heretofore in use in that its action is uniform, regardless of the character of the material upon which it is clamped. In the figure referred to it will be observed that the material under the two jaws varies materially in thickness; but as the application of pressure imposed by the clamp-lever 1 is always upon the pivot-screws 12 midway between the jaws 9 it is evident that the pressure imposed by each jaw is substantially the same.

The present improvement possesses the advantage of adjustability to place the clamping-jaws in the proper relation with the stitch-forming devices and the clamp-carrying slides in that the bosses 6 are adjustable transversely in their respective slots in the carrying-plate 3, whereby the brackets 7 may be shifted equally in the same direction to move the jaws 9 bodily in such direction, or may be shifted unequally in the same or opposite directions within certain limits for changing either or both the angular and bodily relation of the jaws 9 in respect of the stitch-forming devices and other coöperating parts of the machine.

As the clamp-lever 1 and plate 3 compose the carrying member, to which the jaws 9 are secured by the common pivotal connection disposed in the plane of the needle-opening and knife-slot in the throat-plate, and thus in the line of the buttonhole-slit, it is evident that such component parts of the jaw-carrying member are not necessarily constructed separately and secured together by the fastening-screws 2, as herein shown and described.

In order that the point of application of the clamping pressure imposed by the lever 1 may be located in the proper position to enable the jaws to operate as described in stretching the material to be stitched, it is essential that the common pivotal connection between the jaws and such carrying member be disposed intermediate the work-engaging serrated edges of the jaws and substantially midway between such jaws, and thus in the plane of the center of the needle-opening of the throat-plate, as indicated in the drawings. In the operation of the clamp the serrated work-engaging edges of the same thus constitute relatively receding centers, about which the laterally-offset pivotal connections formed by the pins 12 revolve, which in turn in their movement to-

ward the work force the jaws apart to produce the stretching of the material, as above described.

By the term "common pivotal connection" as employed herein to designate the means whereby the work-engaging jaws are secured to their carrier is to be understood pivotal connections upon a common axial line, the same pivotal pin extending not necessarily continuously through both of the independently-moving clamp-jaws at each end of the carrier.

Having thus set forth the nature of my invention, what I claim herein is—

1. A work - clamp for sewing - machines comprising a carrier, clamp-jaws each movable independently of the other and provided at opposite ends with lateral ears, and common pivotal connections intermediate said carrier and the lateral ears of said jaws.

2. A work - clamp for sewing - machines comprising a carrier, independent clamp-jaws each provided at opposite ends with lateral ears, and common pivotal connections intermediate said carrier and the lateral ears of said jaws, one of said connections being adjustable in respect of said carrier.

3. A work - clamp for sewing - machines comprising a carrier, independent clamp-jaws each provided at opposite ends with lateral ears, and common adjustable pivotal connections intermediate said carrier and the lateral ears of said jaws.

4. A work - clamp for sewing - machines comprising a carrier, independent clamp-jaws each provided at opposite ends with lateral ears formed with stop-shoulders adapted to engage the other said jaw when the clamp is in inoperative position, and common pivotal connections intermediate said carrier and the lateral ears of said jaws.

5. A work - clamp for sewing - machines comprising a carrier, independent clamp-jaws each provided at opposite ends with lateral ears formed with stop-shoulders adapted to engage the other said jaw when the clamp is in inoperative position, common pivotal connections intermediate said carrier and the lateral ears of said jaws, and springs for normally pressing said jaws together with the stop-shoulders of the one in contact with the other.

6. A work - clamp for sewing - machines comprising a carrier, clamp-jaws each movable independently of the other, and common pivotal connections for said carrier and jaws disposed between the latter.

7. A work - clamp for sewing - machines comprising a carrier and clamp-jaws each movable independently of the other and provided at opposite ends with common pivotal connections for securing the same together and to said carrier, said connections being disposed intermediate the carrier and the operative portions of the clamp-jaws.

8. A work - clamp for sewing - machines comprising a pair of clamp-jaws each movable independently of the other, and a carrier therefor, lateral ears formed at opposite ends of each of said jaws, dependent lugs upon said carrier, and common pivotal pins each connecting together and to one of the dependent lugs of said carrier the lateral ears at corresponding ends of said jaws.

In testimony whereof I have signed my name to this specification in the presence of two subscribing witnesses.

GEORGE S. GATCHELL.
